UNITED STATES PATENT OFFICE

ROBERT S. SCHMIEDER, OF MILWAUKEE, WISCONSIN, ASSIGNOR, BY MESNE ASSIGNMENTS, TO MILCOR STEEL COMPANY, OF MILWAUKEE, WISCONSIN, A CORPORATION OF DELAWARE

IMITATION PLASTER

Application filed April 6, 1928. Serial No. 267,947.

This invention relates in general to an imitation plaster constituted of sheet metal and more particularly to a rough texture plaster, for instance a rough texture plaster of the 5 style of the so-called Spanish plaster which is constituted of metal sheets.

In carrying out certain types of architecture and certain schemes of interior decorating, it has been found desirable and advantageous to utilize for the walls and ceilings, 10 rough texture plaster or so-called Spanish plaster. This type of plaster blends in well with the Spanish style of architecture and is becoming increasingly popular. In many instances it has been desirable to employ metal 15 ceilings and metal side walls, as the ceilings and side walls so constituted have a great many advantages. But, heretofore, it has been impossible to utilize metal ceilings and 20 side walls where a rough texture or Spanish style of interior surfacing was desired as the only known means of affording such ceiling and side walls surfacing was to work up this 25 texture in the plaster prior to its setting.

One of the principal objects of the present 30 invention is to provide an imitation plaster constituted of sheet metal and yet having its external surface of rough texture or of Spanish plaster formation. While the side walls and 35 ceilings so constituted are made up of metal sheets, the sheets are so constructed and so assembled that the resulting side walls and ceilings present apparently a single continuous surface having the irregular formation, 40 the rough texture, and the other characteristics of the ordinary Spanish plaster or of other style rough texture plaster simulated.

In carrying out the present invention, 45 metal sheets are stamped by means of dies so that their external surfaces are of irregular relief and intaglio formation of the character of rough texture plaster. One side edge of each sheet and one end edge thereof are offset while the other side edge and the other 50 end edge lie in the same mean plane as the major portion or the body of the sheet. The side edge portions are of identical irregular formation and the same is true of the end edges so that when the side edges and the end 55 edges of adjacent sheets overlap, the features 60 of their relief and intaglio formation will register and interfit to conceal the joints and give the appearance of a continuous plaster surface.

Other objects and advantages reside in certain novel features of the construction, arrangement and combination of parts which will be hereinafter more fully described and particularly pointed out in the appended 65 claims, reference being had to the accompanying drawings forming a part of this specification, and in which:

Figure 1 is a fragmentary plan view showing a portion of a ceiling made up of metal sheets embodying the present invention;

Figure 2 is a detail plan view of one of the sheets;

Figure 3 is a fragmentary sectional view taken on line 3—3 of Figure 4;

Figure 4 is a fragmentary sectional view 70 taken on line 4—4 of Figure 3; and

Figure 5 is a diagrammatic view showing the manner of reproducing opposed edges of the original or matrix from which the 75 sheets are produced.

Referring to the drawings, the numeral 1 designates a section of the imitation plaster embodying the present invention. As illustrated, this section 1 consists of a sheet of metal stamped by means of dies to have the 80 relief and intaglio formation of rough texture plaster or the so-called Spanish plaster. In other words, throughout its entire extent, portions of the metal of the sheet are displaced inwardly and outwardly to provide 85 prominences and recessions or ridges and valleys of irregular formation, and of artistic character which blend into each other with a pleasing and decorative effect. While one 90 design or one type of rough texture plaster is shown, it is obvious that the style or design of the rough texture may be varied. One side edge portion 2 of each sheet is offset inwardly from the mean or average plane of the main portion of the sheet as shown to advantage 95 in Figures 2 and 4, while the other side edge portion 3 thereof lies in the same mean plane as the body portion or major portion of the sheet. These side edge portions 2 and 3 are 100 of identical corresponding formation, that is

to say, the prominences and recessions or the relief and intaglio formation of one corresponds exactly to the prominences and recessions or relief and intaglio formation of the other. With this construction, when the side edge portion 3 of one sheet is positioned to overlap the side edge portion 2 of an adjacent sheet, the prominences and recessions of the edge portion 2 will register and snugly interfit with the prominences and recessions of the edge portion 3. One end portion 4 of each sheet is offset inwardly in a manner similar to the offsetting of the edge portion 2 while the other end portion 5 lies in the mean plane of the sheet and these end edge portions 4 and 5 are of identical or corresponding formation to register and interfit with the overlapping end edges of adjacent sheets.

The sheet metal sections 1 are assembled in side wall or in ceiling as illustrated in Figure 1, the edges of the sheets overlapping and interfitting so that the surfaces of the individual sheets blend into an apparently single continuous surface having the irregular formation, the rough texture, and the other characteristics of Spanish plaster. An ornamental border 10 may surround the sheets when assembled in a ceiling.

In producing the sheet metal sections embodying this invention, a matrix, that is an original section of plaster, mud, clay or other plastic of proper consistency, is worked up by an expert plasterer and is of the size of the sheet metal section to be produced. Of course, in this original the edges are of diverse irregular formation. To obtain identity or corresponding formation between the two side edges, and between the two end edges, an impression is made of one side edge portion and of one end edge portion and the side edge portion and the end edge portion of which the impression is made are reproduced and replace respectively the other side and end edge portions of different formation so that now in the original we have corresponding side edge portions and corresponding end edge portions. In other words, one of the diverse side edges is cut away and replaced by a reproduction of the other side edge and the reproduced side edge portion is then blended in with the major portion of the original. Likewise one of the diverse end edges is cut away and replaced by a reproduction of the other end edge. But the reproduced edge portion now has its previous outer edge or margin located in the body of the matrix and the final margin or outer edge of the reproduced edge portion corresponds in structure and formation to a portion of the body located inwardly of the opposite edge. This will be clear from the diagram shown in Figure 5. The original side edge portion O' of the matrix M is cut away along the line S. The reproduction RO of the side edge portion 2 is now placed in the space

previously occupied by the original edge portion O' but the edge a now lies in the body of the matrix and the edge b is the marginal edge. The body of the matrix is then blended in with the reproduced edge portion RO so that the features of the edge portion RO have continuations in the body of the matrix. The end edges are made to correspond in the same way. From the original or matrix having these characteristics, the dies are produced in the usual manner and these dies are employed to stamp out sheet metal sections having the characteristics of Spanish plaster and the edge portions adapted to interfit and to blend the features of one sheet into the features of another. With a metal sheet stamped or otherwise fashioned to have the relief and intaglio formation of rough texture or Spanish plaster, the resulting structure is constituted of a multiplicity of prominences and recessions, or ridges and valleys, and the ridges and valleys are of irregular and varying occurrence and of varying or irregular size and shape. Thus the surface of the sheet along any edge presents a series of ridges and valleys, varying in dimensions and shape and occurring at irregular intervals along the edge. The matching of such sheets in a wall or ceiling so that all the sheets will blend into an apparently single continuous plaster surface presents a very difficult problem which this invention solves by constructing the opposed edges of each sheet to be corresponding in formation, that is, to be made up of ridges and valleys or other similar features of the same size and shape and of the same location as above described, whereby the ridges and valleys of the meeting edges of adjacent sheets register and interfit snugly when overlapped in the assembly.

I claim:

1. A covering for ceilings, walls, and the like, comprising a plurality of sheets of sheet material arranged in the same plane with their edges in joint forming relation, said sheets each having an irregular relief and intaglio design formed on the external surface thereof to represent rough texture plaster, the design on each sheet being distributed entirely thereover and continuing to and through the edges of the sheet so as to continue the design on the body portions of the sheets across the edges thereof to conceal the joints and give the appearance of a single continuous surface of irregular formation in keeping with the design on the body portions of the sheets.

2. A covering for ceilings, walls and the like, comprising a plurality of sheets of sheet material arranged in the same plane with their edges in overlapping relation, said sheets each having an irregular relief and intaglio design formed on the external surface thereof to represent rough texture plas-

ter, the design on each sheet being distributed entirely thereover and continuing to and through the edges of the sheets so that the design at the edges of the several sheets will 5 match and interfit and continue across the overlapping portions of the sheets to conceal the joints and give the appearance of a single continuous surface of irregular formation in keeping with the design on the body portions of the sheets.

10 3. A covering for ceilings, walls and the like, comprising a plurality of sheets of sheet metal arranged in the same plane with their edges in overlapping relation, said sheets each 15 having an irregular relief and intaglio design stamped therein to represent rough texture plaster, the design on each sheet being distributed entirely thereover and continuing to and through the edges of the sheet, said sheets 20 where they overlap having the edge of one sheet offset rearwardly from the mean plane of the body portions of the sheets to continue the design of the body portions of the sheets across the edges thereof, the design in the 25 overlapping edges of the several sheets being complementary to match and interfit.

4. A section for use in a covering for ceilings, walls, and the like, comprising a sheet of sheet metal having an irregular relief and 30 intaglio design formed on the external surface thereof to represent rough texture plaster, the design on the sheet being distributed entirely thereover, and continuing to and through the edges of the sheet, said sheet having 35 certain of its edges in the mean plane of the body portion of the sheet and the other of its edges offset rearwardly from said plane to overlap and be overlapped respectively by the corresponding edges of other sheets used 40 in connection therewith.

In witness whereof, I hereto affix my signature.

ROBERT S. SCHMIEDER.
